SAFETY EMBLEM

Hugh Will Stephenson, Sheffield, and Thomas H. Burton, Florence, Ala.

Application November 5, 1938, Serial No. 238,954

6 Claims. (Cl. 40—130)

Our invention relates to safety emblems adapted for use in connection with traffic control.

One of the principal objects of our invention is to provide an emblem designed to be mounted on vehicles or placed on highways and the like and which is provided with suitable indicia appealing to vehicle operators and pedestrians to avoid negligent and reckless driving.

10 Another object of our invention is to provide an emblem of the above described character equipped with signalling means for attracting attention thereto and thereby propagandize the minds of vehicle operators and pedestrians with 15 the necessity of safe and careful driving and strict compliance with traffic regulations in order to avoid accidents and resultant injuries and deaths thereby.

20 A further object of our invention is to provide an emblem or device of the above described character which is simple in construction, durable in use, attractive in appearance, economical in manufacture and easy of attachment to vehicles and other supports.

25 Other objects and advantages will be apparent from the following description, appended claims and annexed drawings.

30 Referring to the drawings wherein like reference characters designate like parts throughout the several views:

Figure 1 is a front elevation of our invention.

Figure 2 is a sectional view taken on the line 2—2 of Figure 1.

35 Figure 3 is a rear disassembled perspective view of our invention.

40 In practicing our invention, as illustrated in the drawings, we provide a signal plate 1 having fixed to the rear face 2 thereof the upper end section of a support arm 3 by means of bolts 4 extending through said plate and arm. Secured to the upper end section of the arm 3 and on the rear face thereof is the lower end section of a bracket 5 and through which the bolts 4 likewise extend, suitable nuts being provided on the bolts 4 for securing the plate, bracket and support in connected relation.

45 The bracket 5 is provided with an upper end section 6 of an L-shaped configuration and integrally connected to the lower section. The upper end of the upper section is bifurcated to define a slot 7 through which extends an electric cable 8, one end of which is connected to an electric light socket 9 mounted within a light housing 10 fixed to the horizontally disposed portion of the upper section. The opposite end

of the cable is connected to a source of electric energy (not shown) while the socket 9 is provided with an electric bulb 11.

The housing 10 is provided with a closed back and an open front and the marginal or front edge section of the housing, defining the open front, is flared to provide a seat 12 on which is positioned a colored lens 13, the latter being retained on said seat and within the front edge section by engagement of the upper portion of the plate 1 as clearly illustrated in Figure 2 of the drawings. The upper portion of the plate is formed with an opening 14 of a desired and attractive configuration, for instance star-shaped. Said opening 14 constitutes a window 15 and is disposed in front of the lens 13 whereby light rays from the bulb 11 are projected therethrough.

The front face of the plate 1 is provided with indicia or reading matter 15 of such a character 20 as to urge safe driving and with illustrations 16, for instance children at play, for the purpose of instilling the idea of safe driving in the minds of vehicle operators by appealing to their inherent instinct for the preservation of life. The 25 lower end of the arm 3 is provided with a clamp 17 secured thereto by means of nuts and bolts 18 whereby to secure the emblem to the bumper of a vehicle or other suitable support.

It will be noted that when the plate 1, arm 30 3 and bracket 5 are secured together in fixed relation the upper portion of the plate engages the front edge section of the housing 10 and contacts therewith to maintain the lens 13 within the open end of the housing and covering the 35 window 14 and to preclude displacement of the lens therefrom. In order to enhance the appearance of and preclude sharp projecting corners and edges, the plate is provided with rolled marginal edges 19, the lower one of which is slotted 40 as at 20 to receive the arm 3 extending subjacent the plate as clearly illustrated in Figures 2 and 3 of the drawings.

It is obvious that the invention is not confined to the herein described use therefor as it may 45 be utilized for any purpose to which it is adaptable. It is therefore to be understood that the invention is not limited to the specific construction as illustrated and described, as the same is only illustrative of the principles of operation, which are capable of extended application in advance forms, and that the invention comprehends all construction within the scope of the appended claims.

Having thus described our invention we claim: 55

1. An emblem comprising, a plate formed with a window, a bracket connected to said plate, a housing mounted on said bracket and having an open front end engaging said plate and bounding said window, said front end of said housing provided with a seat adjacent said window, a lens mounted on said seat and covering said window, said bracket coacting with said plate to maintain said front end of said housing in engagement with said plate and said lens on said seat and a light source in said housing for illuminating said lens and accentuating said window to attract attention to said plate.
2. An emblem comprising, a plate having front and rear faces and formed with a window and provided with safety appealing indicia on said front face, a bracket connected to said plate, a housing mounted on said bracket and having an open front end engaging said rear face of said plate and bounding said window, said front end of said housing formed with a seat adjacent said window, a lens mounted on said seat and covering said window, said bracket coacting with said plate to maintain said front end of said housing in engagement with said rear face of said plate and said lens on said seat and against said rear face of said plate, and means within said housing for illuminating said lens and accentuating said window to attract attention to said indicia.
3. The elements of claim 1 as set forth and defined therein including, means connecting said plate to said bracket in fixed relation for maintaining said window aligned with said lens.
4. The elements of claim 2 as set forth and defined therein including, means connecting said plate to said bracket in fixed relation for maintaining said window aligned with said lens.
5. An emblem comprising, a plate formed with a window, a bracket connected to said plate, a housing mounted on said bracket and having an open front end engaging said plate and bounding said window, said bracket coacting with said plate to maintain said front end of said housing in engagement with said plate, and a light source in said housing for illuminating and accentuating said window to attract attention to said plate.
6. An emblem comprising, a plate formed with a window, a bracket connected to said plate, a housing mounted on said bracket and having an open front end engaging said plate and bounding said window, and a lens mounted in said open front end and covering said window, said bracket coacting with said plate to maintain said front end in engagement with said plate and said lens covering said window, and a light source in said housing for illuminating said lens and accentuating said window to attract attention to said plate.

HUGH W. STEPHENSON.
